UNITED STATES PATENT OFFICE

165,635

DECORATIVE CHESS HORSE LAMP

Earle F. Chapman, South Braintree, Mass.

Application January 7, 1950, Serial No. 7,061

Term of patent 3½ years

(Cl. D48—20)

To all whom it may concern:

Be it known that I, Earle F. Chapman, a citizen of the United States, and a resident of South Braintree, in the county of Norfolk, and State of Massachusetts, have invented a new, original, and ornamental Design for a Decorative Chess Horse Lamp, of which the following is a specification, reference being had to the accompanying drawing, forming a part hereof.

Fig. 1 is a side perspective view of a decorative chess horse lamp, showing my new design, the opposite side being the same.

Fig. 2 is a front elevational view of the chess horse lamp;

Fig. 3 is a rear elevational view of the chess horse lamp.

The dominant features of my design are shown in solid lines in the drawing.

I claim:

The ornamental design for a decorative chess horse lamp, substantially as shown and described.

EARLE F. CHAPMAN.
